(57) **CLAIM**

The ornamental design for a portable FM radio and Bluetooth speaker, as shown and described.

DESCRIPTION

FIG. 1 is a front elevational view of a portable FM radio and Bluetooth speaker showing my new design;

FIG. 2 is a rear elevational view thereof;

FIG. 3 is a left side view thereof;

FIG. 4 is a right side view thereof;

FIG. 5 is a top plan view thereof;

FIG. 6 is a bottom plan view thereof;

FIG. 7 is a top, front and left side perspective view thereof; and,

FIG. 8 is a bottom, front and right side perspective view thereof.

The broken lines in the drawings illustrate portions of the portable FM radio and Bluetooth speaker which form no part of the claimed design.
